(57) **CLAIM**

The ornamental design for a firearm, as shown and described.

DESCRIPTION

FIG. 1 is a top, front, right perspective view of a firearm showing a first embodiment of my new design;
FIG. 2 is a bottom, front, left perspective view thereof;
FIG. 3 is a top, rear, right perspective view thereof;
FIG. 4 is a bottom, rear, left perspective view thereof;
FIG. 5 is an enlarged perspective view of the claimed area shown in FIG. 2 thereof;
FIG. 6 is a bottom perspective view of FIG. 5 thereof;
FIG. 7 is an enlarged perspective view of the claimed area shown in FIG. 1;
FIG. 8 is a bottom perspective view of FIG. 7 thereof;
FIG. 9 is a top, front, right perspective view of a firearm showing a second embodiment of my new design;
FIG. 10 is a bottom, front, left perspective view thereof;
FIG. 11 is a top, rear, right perspective view thereof;
FIG. 12 is a bottom, rear, left perspective view thereof;
FIG. 13 is an enlarged perspective view of the claimed area shown in FIG. 10 thereof;
FIG. 14 is a bottom perspective view of FIG. 13 thereof;
FIG. 15 is an enlarged perspective view of the claimed area shown in FIG. 9; and,
FIG. 16 is a bottom perspective view of FIG. 15 thereof.
The uneven-length broken lines represent unclaimed boundaries of the claimed design. The even-length broken lines showing the remainder of the firearm are for environmental purposes only and form no part of the claimed design.
